STACKABLE RACK FOR FOLDING CHAIRS

Jan Machielse, Erving B. Morgan, and Gerald L. Weaver,
Grand Rapids, Mich., assignors to American Seating
Company, Grand Rapids, Mich., a corporation of New
Jersey

Filed May 19, 1958, Ser. No. 736,162

1 Claim. (Cl. 211—27)

The present invention relates to racks and more particularly to stackable racks for folding chairs.

The primary objects of the invention are to provide an improved rack for the storage of folded folding chairs when the chairs are not in use; to provide such a rack which is so constructed as to be stackable with other, like racks, so that the loaded racks can be stacked up and thus occupy a minimum of floor area; and in general to provide such a stackable rack which is sturdy though economical in construction.

An illustrative embodiment of the invention is shown in the accompanying drawings, wherein

Figure 1 is a perspective view showing three of the new racks loaded with folding chairs and stacked one upon another, and also showing a fork truck for stacking and unstacking the racks;

Figure 2 is a side elevational view of one of the new racks;

Figure 3 is a top plan view thereof;

Figure 4 is an end elevational view of one rack with another rack, shown fragmentarily, stacked thereon; and

Figure 5 is a greatly enlarged, fragmentary vertical sectional view of parts thereof taken on line 5—5 of Figure 4.

Referring now in detail to these drawings the new rack as shown is primarily designed to accommodate folding chairs 10 when in their folded condition for storage, although it might easily be modified to accommodate other articles. Each rack comprises four upright tubular metal corner posts 11 arranged in rectangular plan with the width of the plan slightly greater than the combined widths of two of the folding chairs 10, and an article-supporting bed generally designated 12 secured to the corner posts 11 near the lower ends of said posts.

As here shown, the supporting bed 12 comprises side angle bars 13, end angle bars 14, and longitudinal inner angle bars 15. The side and end angle bars 13, 14 have their ends secured as by welding to the corner posts 11, and these angle bars 13, 14 have vertical flanges and horizontal flanges extending inwardly from the lower edges of the vertical flanges. The inner angle bars 15 extend lengthwise of the rack near the longitudinal center of the rack and have their ends secured as by welding to the end angle bars 14. These inner angle bars 15 have vertical flanges and horizontal flanges extending outwardly from the lower edges of the vertical flanges. The side angle bars 13 and the inner angle bars 15 form pairs of supports for two rows of the folded chairs 10, the long legs of the chairs resting on the horizontal flanges of these angle bars 13 and 15.

2

The rack is braced and strengthened by means of horizontal bars or rods 16 connecting the end pairs of corner posts 11 near their upper ends, side braces 17 of metal tubing flattened at their ends and secured to the corner posts 11 and to the side angle bars 13, end braces 18 of strip stock secured to the corner posts 11 and to the end angle bars 14, and bottom braces 19 of angle bar stock extending transversely of the rack and secured to the under surfaces of the side and inner angle bars 13 and 15. These parts are all desirably secured together by means of welding.

The upper ends of the corner posts 11 have metal domes 20 fitted thereto and preferably welded in place. The lower ends of the corner posts 11 have downwardly divergent cones 21 of heavy gage pressed metal stock secured thereto as by means of welding 22 indicated in Figure 5. It will be seen that the cones 21 of the corner posts 11 of each rack are adapted to receive the domed upper ends of the corresponding corner posts 11 of a like rack so that one rack may be stacked on top of another. Figure 1 shows three of the racks loaded with folded chairs and stacked one upon another. The stacking and unstacking is accomplished by means of the fork truck 23 also seen in Figure 1.

It will thus be seen that the invention provides a novel and highly useful stackable folding chair rack, and while but one specific embodiment of the invention has been herein shown and described it will be understood that numerous details may be altered or omitted without departing from the spirit of the invention as the same is defined by the following claim.

We claim:

In a stackable rack for folding chairs: four upright tubular metal corner posts of greater height than said folding chairs and arranged in rectangular plan with the width of the plan slightly greater than the combined widths of two of the folding chairs; a pair of side angle bars and a pair of end angle bars connecting the corner posts at the sides and ends of the rack near the lower ends of the corner posts, said angle bars having vertical flanges and horizontal flanges extending inwardly from the lower edges of the vertical flanges; a pair of inner angle bars extending lengthwise of the rack near the longitudinal center thereof and having their ends connected to said end angle bars, said inner angle bars having vertical flanges and horizontal flanges extending outwardly from the lower edges of the vertical flanges and forming with the side angle bars pairs of spaced supports for the legs of the folding chairs; metal domes fitted to the upper ends of said corner posts; and downwardly divergent metal cones secured to the lower ends of said corner posts and adapted to receive the domed upper ends of the corresponding corner posts of a like rack whereby one rack may be stacked on top of another.
